E. G. REISING.

FIREARM.

APPLICATION FILED JAN. 11, 1918.

1,381,016.

Patented June 7, 1921.

UNITED STATES PATENT OFFICE.

EUGENE G. REISING, OF EAST HARTFORD, CONNECTICUT, ASSIGNOR TO THE HARTFORD MACHINE GUN COMPANY, OF HARTFORD, CONNECTICUT, A CORPORATION OF CONNECTICUT.

FIREARM.

1,381,016.

Specification of Letters Patent. Patented June 7, 1921.

Application filed January 11, 1918. Serial No. 211,347.

To all whom it may concern:

Be it known that I, EUGENE G. REISING, a citizen of the United States, residing at East Hartford, in the county of Hartford, 5 and State of Connecticut, have invented a new and Improved Firearm, of which the following is a specification.

My invention relates more especially to that class of firearms that are of automatic 10 action, that is, firearms in which the breech-bolt action is caused by gases of explosion, and an object of my invention, among others, is to provide a firearm that shall be particularly efficient in its operation and 15 little liable to become inoperative in action.

One form of such a device embodying my invention and in the construction and use of which the objects herein set out, as well as others, may be attained, is illustrated in 20 the accompanying drawings, in which—

Figure 1 is a view partially in side elevation and partially in section of a firearm embodying my invention, the breech-bolt being shown in its rearward position.

Fig. 2 is a detail view, scale enlarged, of 25 a portion of my improved firearm with parts broken away to show the construction and operation of the breech-bolt lock and sear, the breech-bolt being shown in its forward position.

Fig. 3 is a detail view, scale enlarged, in cross section, through the device on plane denoted by dotted line 3—3 of Fig. 2.

In the accompanying drawings the numeral 35 5 indicates the receiver of my improved firearm, comprising a portion of the frame, the latter embodying a handle 6 with a trigger guard 7. A barrel 8 is secured to the receiver in any desired manner and a 40 case 9 is secured underneath the barrel and incloses operative parts of the firearm, which parts may include an actuating block 10 having a piston 11 operated by pressure through a port 12 opening laterally from 45 the bore of the barrel toward its muzzle end and communicating with a piston chamber 13 located in a gas-head 14 secured to the barrel, the pressure of the exploding gases upon the piston being controlled by a valve

15 secured to the block 10 and controlling 50 the exhaust through the port 12. My invention herein illustrated and described, while not limited in its use to any specific type of firearms, is especially applicable to the firearm illustrated and described in 55 my copending application Serial Number 104,878, filed June 21st, 1916, to which application reference is hereby made for such further understanding as may be desired of the construction and operation of those 60 parts not embodying the invention forming the subject matter of this application.

An action rod 16 is pivotally attached at one end to the block 10 and at its opposite end to an action bar 17, said bar being pivotally secured to a breech-bolt retaining lever or primary locking member 18 pivotally mounted in the lower end of a breech-bolt chamber 19 in the receiver. The outer end of said lever is forked, the branches 20 65 of said fork being adapted to enter recesses 21 formed in opposite sides of a breech-bolt 22, near the rear end of said bolt. The ends 24 of the lever are formed and adapted to rest against breech-bolt retaining shoulders 25 formed at the lower front edge of 70 the recesses 21, these shoulders being diagonally arranged to correspond to the diagonal position of the ends 24 of the retaining lever 18 when the latter is in its forward 75 position, and as shown in Fig. 2 of the drawings.

The breech-bolt 22 is suitably mounted for reciprocating movement in the chamber 19, said bolt, in its forward position, encountering cartridges 26 located in a carrier belt 27 supported on feed wheels 28—29 rotatably mounted in a carrier chamber 30 located in the receiver forward of the breech-bolt chamber and under the same. 85 90

The breech-bolt, when a cartridge is fired, is held by the retaining lever 18 against backward movement under the force of the gases of explosion until the lever is released by the action bar and action rod 17—16 that 95 are operated by the action of the gases through the port 12 and upon the piston 11 that moves the block 10, the latter operating

said action bar and action rod. In order that the pressure upon the breech-bolt shall not be transmitted unduly, by reason of the diagonally arranged shoulders engaging the diagonally positioned end of the lever, to the walls of the receiver at the upper part thereof, I have provided means for supporting the breech-bolt at the time this pressure takes place.

10 In effecting this result I provide a resistance block 31 that is inserted in a recess 32 in the top wall of the chamber 19 in the receiver. In the preferred form of construction and as shown herein the recess 32 is formed by cutting a dove-tailed shaped groove across the top wall of the chamber 19 from one side of said chamber, this open side of the chamber being closed by a cover plate 33. The block is of a length substantially equal to the width of the chamber 19 and the cover plate holds it securely in place. A retaining notch 34 is formed in the bottom surface of said block to receive a resistance bar or secondary locking member 35 that is carried by the breech-bolt 22.

15 In the preferred form of construction this bar has actuating pins 36 projecting through holes in the breech-bolt and opening out at the shoulders 25. The bar 35 is located 20 in a slot 37 cut across the top of the breech-bolt, and the pins 36 are of lengths sufficient 25 to project beyond the surfaces of the shoulders 25 when the bar is seated in the bottom of its slot. The ends of the pins are preferably rounded, and when the lever 18 is in 30 its forward position it will act upon said pins and force the bar 35 into the retaining notch 34. A retaining bar releasing plunger 38 is located in a well 39 in the top of the 35 receiver, this well being closed in any suitable manner, as by means of a plug 40, and a spring 41 is employed to force the plunger against the bar 35 to disengage said bar from the notch 34 when the lever 18 is 40 moved from contact with the pins 36 whenever the action is operated by hand, but in acting automatically the pressure of the breech-bolt against the bar forces the latter against the inclined surface of the retaining notch 34, this pressure being sufficient to 45 disengage the bar from said notch.

50 A firing pin 42 is carried in the breech-bolt and it has a shoulder 43 adapted to be engaged by a sear 44 pivotally mounted in the upper side of the breech-bolt and spring 55 pressed into position to engage said shoulder, as shown in Fig. 2 of the drawings. This sear has a finger 45 engaged within a recess 46 in the side of the resistance bar 35.

55 A trigger 47 pivotally mounted in the frame and extending within the trigger guard 7, has an action bar holding lip 48 adapted to engage a holding notch 49 in the action bar 17.

60 In the operation of the gun, the trigger

being free from pressure upon its front edge as by a human finger and the trigger being forced forward by its spring plunger 50, in a manner common to firearms, the action bar 17 as it moves backwardly will be caught 70 near the rearward limit of its play and held in this position, the breech-bolt retaining lever and breech-bolt consequently being held in their retracted or rearward positions. This leaves the breech of the barrel 75 open and the carrier within the frame in condition for a circulation of air whereby the cooling effects are increased, such cooling taking effect whenever the gun is not in action.

80 The trigger being pulled the breech-bolt will be released and will be forced forward by the action of the main spring 51, in which movement it will insert a cartridge into the breech of the barrel as hereinbefore 85 described. In this forward movement the shoulder 43 on the firing pin will be engaged by the point 52 of the sear and momentarily arrested.

85 In this forward movement of the breech-bolt the lever 18 is also swung to its forward position and as the ends 24 of the lever move against the retaining shoulder 25 they engage the actuating pins 36 and force the resistance bar 35 into the retaining notch 90 34. This bar is now in position to resist thrust upon the breech-bolt caused by the forces of the gases of explosion, this resistance being in a line substantially lengthwise 95 of the frame, application of lateral force 1 from such causes being substantially removed.

95 The recess 46, within which the finger 45 is located, is of a sufficient width to permit initial movement of the resistance bar 35 100 without movement of the sear. At the termination of the movement of the resistance bar, however, the bottom of the recess will encounter the finger 45 and the sear will be moved upwardly and disengaged from 105 the firing pin, and the latter will be forced forward by its spring and thereby cause a cartridge to be exploded, upon which the breech-bolt will be thrown to its rearward position in a manner hereinbefore described. 110

115 From this it will be seen that if pressure upon the trigger be retained the gun will continue to be fired so long as such pressure exists. Upon the pressure on the trigger being released, the action bar will be caught 120 in its next rearward movement and the firing of the gun will thus cease with the parts in their rearward and open position as hereinbefore described.

125 In accordance with the provisions of the patent statutes, I have described the principles of operation of my invention, together with the device which I now consider to represent the best embodiment thereof; but I desire to have it understood that the device 130

shown is only illustrative and that the invention may be carried out by other means.

I claim—

1. A firearm including a receiver and firing mechanism located therein and including a movably mounted breech-bolt operative by the gases of explosion, means for locking the breech-bolt in its closed position, separate locking means movably mounted to support the breech-bolt and reduce results of the force applied to said locking means by firing action, said supporting means being positioned by the breech-bolt locking means to transmit said force from the breech-bolt to the receiver, and means for initially actuating one of said locks without actuating the breech-bolt.
2. A firearm including a receiver, a breech-bolt movably mounted therein and operative by the gases of explosion, one of said parts having a retaining notch and the other a movably mounted resistance member, means for locking the breech-bolt in its closed position and for engaging said resistance member with said notch to reduce the effects of the force applied to the breech-bolt by firing action, and means for operating said locking means without actuating the breech-bolt.
3. A firearm including a receiver having a retaining notch, a breech-bolt movably mounted in the receiver, a resistance bar carried by the breech-bolt, a pin projecting from said bar through the breech-bolt, and a breech-bolt retaining lever mounted to engage said pin and move the bar into said notch.

4. A firearm including a receiver having a recess extending across the upper wall thereof, a resistance block located within said recess and having a retaining notch therein, a breech-bolt movably mounted in the receiver, means for moving the breech-bolt, and a resistance member carried by the breech-bolt to engage said notch and resist backward movement of the breech-bolt.

5. A firearm including a receiver having a breech-bolt chamber therein closed on one side and open on its opposite side and having a recess cut across its top wall, a resistance block movable into said recess from the side of the chamber and having a retaining notch, a cover to close said chamber and hold said block in place, a breech-bolt movably mounted in said chamber, and a resistance member carried by the breech-bolt to enter said notch to resist force applied to the breech-bolt.

6. A firearm including a receiver having a retaining notch in the wall thereof, a breech-bolt movably mounted in the receiver, a breech-bolt actuating lever to engage said breech-bolt and hold it against backward movement, and a resistance member mounted in the breech-bolt and having a pin to

be engaged by said lever when the breech-bolt is in its forward position and to force said resistance member into the retaining notch.

7. A firearm including a receiver having a retaining notch therein, a breech-bolt movably mounted in the receiver and having a diagonally arranged shoulder, a breech-bolt retaining lever pivotally mounted to engage said shoulder and hold the breech-bolt in its forward position, and a resistance member carried by the breech-bolt and having a pin projecting out at the surface of said diagonally arranged shoulder to be engaged by said lever.

8. A firearm including a receiver, a breech-bolt movably mounted therein, a firing pin carried by the breech-bolt, a movably mounted sear adapted to engage the firing pin, means for operating the sear, means including an action bar for actuating the breech-bolt, and a trigger to engage said action bar and hold the breech-bolt in its rearward position.

9. A firearm including a receiver, a breech-bolt movably mounted in the receiver, a firing pin carried by the breech-bolt, a sear movably mounted on the breech-bolt to engage said firing pin, a resistance member movably carried on the breech-bolt and having a recess to receive a projection from the sear, means for operating the resistance member, and means for controlling the movement of the breech-bolt.

10. A firearm including a receiver, a breech-bolt movably mounted in the receiver, a firing pin carried by the breech-bolt, a sear movably mounted on the breech-bolt, a resistance member movably mounted on the breech-bolt and having a recess to receive a projection from the sear, means for operating the resistance member, and a trigger mounted to control operation of the means for operating the resistance member.

11. A firearm including a receiver, a breech-bolt movably mounted therein, a firing pin carried by the breech-bolt, a sear mounted on the breech-bolt to engage said firing pin, a resistance member movably mounted on the breech-bolt and having a recess to receive a projection from said sear, means for operating the breech-bolt and including a lever to engage said resistance member, and a trigger to engage said breech-bolt operating means to control the movement thereof.

12. A firing mechanism for a firearm, said mechanism including a movably mounted breech-bolt operated by the gases of explosion, a lock movably mounted upon and carried by the breech-bolt to hold it in its closed position, a member pivotally mounted and operatively connected with said lock to retain it in its closed position, and an action

bar connected to operate said pivotally mounted member, said action bar being operated by the gases of explosion.

13. A firing mechanism for a firearm, said mechanism including a movably mounted breech-bolt operated by the gases of explosion, a lock movably mounted upon and carried by the breech-bolt to hold it in its closed position, a second lock for the breech-

bolt including a member pivotally mounted 10 and operatively connected with the first mentioned lock to retain it in its closed position, and an action bar connected to operate said pivotally mounted member, said action bar being operated by the gases of 15 explosion.

EUGENE G. REISING.
